MACHINE FOR OPERATING UPON BOBBINS

Russell P. Drake, Caledonia, Robert E. Borchardt, Rockford, and Charles B. Crandall, Loves Park, Ill., assignors to Barber-Colman Company, Rockford, Ill., a corporation of Illinois

Application September 11, 1952, Serial No. 309,122

11 Claims. (Cl. 242—35.5)

The invention relates to a machine for operating upon bobbins, and more particularly, bobbins of the filling wind type. In Marcellus Patent No. 2,409,639, dated October 22, 1946, is disclosed a machine for winding bobbins of this type and the present invention has for its general aim the provision of a mechanism, preferably in the form of an attachment to such bobbin winding machines, whose function it is to remove from the butt end of the bobbin any surplus yarn which may have been wound thereon in the operation of the winding machine.

Upon the completion of the operation of winding a bobbin in a machine such as that of the Marcellus patent, the bobbin is released or doffed from its normal winding position in which it is held between a chuck gripping the butt end and a centering slide supporting the tip end, and following such doffing operation the supply thread is sheared from the wound bobbin and clamped in the chuck into which a new or empty bobbin has been placed for the next winding cycle. It sometimes happens that at the beginning of this winding operation a number of turns of yarn are wound upon the butt end of a bobbin in advance of the normal winding operation. The presence of such surplus yarn on the wound bobbin is objectionable because it tends to foul the yarn as it is being unwound from the bobbin, resulting in breakage of the thread and in some instances causing imperfections in the woven cloth as may occur if the surplus end is broken off and not properly removed.

With the foregoing in view, the primary object of the present invention is to provide for the removal in a practical way of any surplus yarn accidentally or unintentionally wound upon the butt end of the bobbin. As disclosed in Peterson Patent 2,696,901, the bobbins produced in the operation of the winding machine are deposited in pockets carried by an endless receiving conveyor and advanced to one end of the machine where they are delivered to a transport conveyor also containing pockets for the reception of the bobbins.

Another object of the present invention is to provide a mechanism for removing surplus yarn from the bobbins which mechanism is especially designed to operate upon the bobbins at a point between the receiving conveyor of the bobbin winding machine and the transport conveyor.

Another and somewhat more specific object concerns a novel mechanism for unwrapping the surplus yarn from a bobbin, withdrawing it as it is unwrapped and finally severing it from the bobbin.

The objects of the invention thus generally stated, together with ancillary advantages, are attained by the construction and arrangement set forth by way of illustration in the accompanying drawings wherein:

Figure 1 is a fragmentary side elevational view showing the surplus material removing mechanism interposed between the receiving conveyor of the bobbin winding machine and the transport conveyor with a driving connection with the receiving conveyor.

2

Fig. 2 is a fragmentary plan view on a somewhat larger scale.

Fig. 3 is a fragmentary longitudinal sectional view taken approximately along the line 3—3 of Fig. 2.

Fig. 4 is a fragmentary perspective view of a wound bobbin with surplus yarn wound about the butt end of the bobbin and taking its usual form of a number of turns.

Fig. 5 is a fragmentary transverse sectional view taken approximately in the plane of line 5—5 of Fig. 1.

Fig. 6 is a fragmentary longitudinal sectional view on a scale substantially larger than that of Fig. 3 and showing more particularly the manner in which the wound bobbins are delivered successively to the surplus yarn removing mechanism.

In the preferred embodiment of the invention, the aforesaid mechanism generally designated A is disposed at the delivery end of a bobbin winding machine B and operative upon the removal of the surplus yarn to transfer the bobbins to a transport conveyor C. The discharge end of the receiving conveyor of the winding machine is shown at the left in Figs. 1 to 3. It comprises a pair of endless chains 10 having spaced pockets 11 mounted thereon, the chains passing over sprockets 12.

The unit A comprises in general a hopper 13 (Figs. 3 and 5) opening toward the discharge end of the bobbin winding machine for the reception of wound bobbins from the receiving conveyor 10. In the bottom of the hopper is a discharge opening normally closed by a trap door 14 and below the opening is located a yarn severing means generally designated 15 for removing from the bobbins b any surplus yarn which may be wrapped about the butt end of the bobbin as shown at b' (Fig. 4). A controlling cam mechanism 16 is operatively associated with the trap door 14 to release bobbins periodically in timed relation to the operation of the supply conveyor, and this cam mechanism additionally removes the bobbins from the severing unit 15 after removal of the surplus yarn, to the transport conveyor C.

The hopper 13 comprises in the form shown a pair of side walls 17 suitably supported on front and rear frame plates 17a and 17b (Fig. 5), an end wall 18 and a bottom wall 19 formed by a stationary plate 20, a yieldably supported drop plate 21 and by the trap door 14. The trap door 14 is so disposed relative to the plates 20 and 21 as to form a trough shaped pocket at the extreme bottom of the hopper in which pocket the bobbin comes to rest for delivery to the severing unit 15 when the trap door 14 is opened.

The side plates 17 respectively guide the butt and tip ends of the bobbin so that in the normal operation bobbins dropped onto the plate 21 roll downwardly into the pocket with the axis of the bobbin extending in a front to rear direction. The plate 21 is yieldably held in closed position by a spring 22 (Fig. 3), this plate being pivoted to swing on a stationary shaft 23. The purpose of this yieldable mounting of the plate 21 is to provide for the contingency that bobbins delivered to the hopper may accidentally become turned in such a way as to clog the passage to the hopper and thus fail to move properly into the pocket at the bottom of the hopper. Should this occur, the accumulated weight of a number of bobbins on the plate 21 will overcome the tension of plate 22 and allow the bobbins to drop onto the floor or into a suitable container.

The severing unit 15 comprises means for rotatably supporting the bobbins upon release from the hopper, including in the present instance a trough shaped block 24 for the tip end of the bobbin, and a pair of rollers 25 (Fig. 5) mounted on spaced parallel axes immediately below the discharge opening normally closed by the trap door 14. The rollers 25 are operatively connected with the receiv-

ing conveyor 10 of the winding machine in a manner which will presently appear. As the bobbin is rotated, the loose or free end of the surplus thread is drawn downwardly by suction means (Figs. 5 and 6) consisting of a duct 26 connected with a suitable exhaust fan 26a, the direction of the rotation of the rolls being such as to cause the thread to unwind from the bobbin as it is withdrawn downwardly by the suction means.

Immediately adjacent and somewhat below the rollers 25 and the withdrawn strand is acted upon by a second pair of rollers 27 provided with relatively sharp intermeshing teeth which operate to break or chew off the strand to an unobjectionable length. To insure free passage of air between the severing rolls 27 the teeth at opposite sides of the rolls are preferably milled off as shown Figs. 5 and 6.

Upon discharge from the hopper the bobbins pass downwardly between a pair of plates 28 and 29 respectively mounted on shafts 30 and 31 (Fig. 3), the tip ends of the bobbin being guided by a stationary plate 32 (Fig. 5) carried by a bracket 32a and the butt ends by a guide member 33, the surfaces being appropriately inclined so as to direct the bobbin into position with the butt ends resting upon the rollers 25 with the tip ends supported in the trough shaped block 24 which are supported by inturned portions 35 of the plate 32. This construction provides supports for the tip and butt ends of the bobbins so as to support the yarn masses clear of contact of any supporting surface.

The cam means 16 has for its primary purpose the periodic operation of the trap door 14 and the actuation of the plates 28 and 29 following the removal of the surplus yarn from the bobbins, to deliver the latter to the transportation conveyor C. In the present instance the cam means 16 is driven from the winding machine through a chain and sprocket connection with the receiving conveyor 10. Thus, the shaft 37 of the receiving conveyor has fast thereon a driving sprocket 38 (Fig. 2) for a chain 39 running over sprockets 40 and 41 (Figs. 3 and 5). Sprocket 40 is mounted on a sub shaft 42 on frame plate 17b, carrying a cam 43.

Cam 43 is a two-lobed cam having a follower 44 (Figs. 3 and 6) normally urged against the cam by a spring 45. Follower 44 is fast on a shaft carrying the trap door 14. A second follower 47 is urged by a spring 48 against the cam. This follower is fast on a rock shaft 47a having rigid therewith a bell crank 49 (Fig. 6), one arm of which is connected by a link 50 and an arm 51 with the shaft 31, and the other arm of which is connected by a link 52 with an arm 53 fast on the shaft 30. Shafts 30 and 31, which carry the guide plates 28 and 29, are thus arranged for operation in unison by the cam 43, the arrangement being such that the plates 28 and 29 are first operated by the cam, the former engaging with the bobbin to shift it onto a downwardly inclined plate 54 for delivery to the transport conveyor, and then upon return of the plates to normal position by the spring 48 as permitted by the cam, the follower 44 is operated to open the trap door and release the next bobbin to the severing unit 15. As shown, the transport conveyor C comprises a plurality of pockets 55 (Fig. 3) into which the bobbins are successively delivered, it being understood that this conveyor is advanced in proper timed relation to the main receiving conveyor.

Chain 39 is also utilized to drive the bobbin supporting rollers 25 of the severing unit, as shown in Fig. 5. Sprocket 41 has a gearing connection 57 with a pair of shafts 58 respectively carrying the rollers 25. The severing rollers 27 are preferably driven directly by a separate motor 59 connected by a shaft 60 with one of the two rollers 27.

By way of summary, in the operation of the bobbin winder, filling-wound bobbins are delivered one by one to the hopper 13, and are successively directed thereby to the severing unit 15. The cam actuated trap door 14 at the bottom of the hopper constitutes in effect an escape-

ment mechanism controlled by the cam 43 so that the bobbins are released to the severing means in timed relation to the operation of the winding machine and more particularly its receiving conveyor 10. Bobbins thus delivered to the severing unit are supported for rotation in a direction to unwind from the butt ends of the bobbins any surplus yarn which may have been wound thereon in the operation of the winding machine. Coincidentally with such rotation of each bobbin, the unwrapped strand is withdrawn and presented to the severing means, namely, to the two rolls 27 with sharpened intermeshing teeth operating to chew off the strand to an unobjectionable length. Upon the lapse of a predetermined time interval following the deposit of the bobbins onto the supporting and rotating means, they are shifted laterally by the operation of the guide plates 28, 29, again under the control of the cam 43, the laterally shifted bobbins being delivered to the pockets 55 of the transport conveyor C.

We claim as our invention:

1. An apparatus for operating upon filling wound bobbins comprising, in combination, means for rotating a bobbin in a direction to unwrap a strand of yarn wound upon its butt end, a pair of rolls disposed below said bobbin rotating means and having intermeshing teeth, and continuously operating means to exert a force other than gravity on the unwrapping strand to draw the same away from the bobbin and present it to said rolls to cut or break off the strand from the bobbin.

2. The combination of a bobbin winding machine having a conveyor for receiving filling wound bobbins, a hopper for receiving the bobbins as they are discharged by said conveyor, bobbin supporting and rotating means, means operative in timed relation to said conveyor for delivering bobbins one by one from said hopper to said supporting and rotating means, the last mentioned means being operative to revolve the bobbins in a direction to unwrap strands of yarn wrapped about the butt ends thereof while leaving the filling intact, strand severing means, and means for presenting the unwrapping strand to said severing means.

3. An apparatus for operating upon filling wound bobbins comprising a hopper, a conveyor for delivering bobbins one by one to said hopper, means for unwrapping from the bobbins strands of excess yarn wound upon the butt ends thereof while leaving the filling on the bobbins intact, and means operative in timed relation to said conveyor to deliver bobbins successively to said surplus strand removing means.

4. In an apparatus for operating upon bobbins, the combination of a hopper for receiving filling wound bobbins, said hopper having a discharge opening and a closure therefor, means for removing excess yarn wound upon the butt ends of the bobbins including a pair of rotating rollers disposed side by side for supporting and rotating the successive bobbins delivered on top of the rollers, and cam means operative first to remove a bobbin from position on said rollers and then to actuate said closure means to deliver a succeeding bobbin from the hopper onto the rollers.

5. Apparatus for operating upon filling wound bobbins, having, in combination, means for supporting and rotating a bobbin to unwrap a strand of yarn wound on the butt end of the bobbin, means defining a suction chamber maintained under a vacuum and disposed adjacent the rotating bobbin to draw the unwrapped end away from the bobbin, and a pair of rotatable rolls disposed between said bobbin and said inlet and having intermeshing teeth shaped to cut or break off the unwrapped strand from the bobbin.

6. In apparatus for removing the surplus yarn wound upon the butt end of a filling wound bobbin, the combination of, a pair of rollers rotatable about adjacent horizontal axes and adapted to receive and support the butt end of a bobbin, a second support axially spaced from said rollers to engage and support the tip of the bobbin

engaging said rollers, the filling of the bobbin being disposed between and out of contact with said rollers and support, means for delivering bobbins one by one sideways and downwardly onto said rollers and support, means for turning said rollers in a direction to unwrap the yarn from the butt end of the supported bobbin, a suction chamber maintained under vacuum and having an inlet spaced below the supported bobbin to draw away the yarn unwrapped from said butt end, and means between the bobbin and said inlet and engageable with the 10 unwrapped yarn and operable to draw the yarn downwardly and break off the same down to the filling of the bobbin.

7. In apparatus for removing the surplus yarn wound upon the butt end of a filling wound bobbin, the combination of, means for supporting and rotating the bobbin including a pair of rollers rotatable about adjacent horizontal axes and adapted to receive and support the butt end of a bobbin and a second support axially spaced from said rollers to engage and rotatably support the tip of the bobbin engaging said rollers, means for delivering bobbins one by one onto said rollers and means for turning said rollers in a direction to unwrap the yarn from the butt end of the supported bobbin, a suction chamber maintained under vacuum and having an inlet spaced below the supported bobbin, and rotary elements having intermeshing teeth and disposed between the bobbin and said inlet to engage and break off said yarn after unwrapping thereof.

8. In apparatus for removing the surplus yarn wound upon the butt end of a filling wound bobbin, the combination of, means for supporting and rotating the bobbin including a pair of rollers rotatable about adjacent horizontal axes and adapted to receive and support the butt end of a bobbin, means for delivering bobbins one by one onto said rollers and means for turning said rollers in a direction to unwrap the yarn from the butt end of the supported bobbin, a suction chamber maintained under vacuum and having an inlet spaced below the supported bobbin, and rotary cutting elements having intermeshing teeth and disposed between the supported bobbin and said inlet to engage and break off said yarn after unwrapping thereof.

9. In apparatus for removing the surplus yarn wound upon the butt end of a filling wound bobbin, the combination of, means for supporting and rotating the bobbin including a pair of rollers rotatable about adjacent horizontal axes and adapted to receive and support the butt end of a bobbin, means for delivering bobbins one by one onto said rollers and means for turning said rollers in a direction to unwrap the yarn from the butt end of the supported bobbin, a suction chamber maintained under vacu-

5

um and having an inlet spaced below the supported bobbin, means disposed between the bobbin and said inlet and operable to engage and break off said yarn after unwrapping thereof, an ejector movable laterally across and above said rollers to roll the bobbin sideways and horizontally off from the rollers, and means for operating said ejector intermittently.

10. In apparatus for removing the surplus yarn wound upon the butt end of a filling wound bobbin, the combination of, two supports for receiving and supporting the butt and tip ends of the bobbin beyond the filling thereon, one of said supports including a pair of rollers rotatable in a direction to unwrap a strand of yarn from said butt end, means for delivering bobbins one by one onto said supports, a chamber maintained under vacuum and having an inlet spaced laterally from the supported butt end of the bobbin, and means disposed between the bobbin and said inlet and operable to engage and break off said yarn after unwrapping thereof.

11. In apparatus for removing the surplus yarn wound upon the butt end of a filling wound bobbin, the combination of, means for supporting and rotating the bobbin in a direction to unwind said surplus yarn down to the end of the filling on the bobbin, said means including a rotary drive member engageable with an end of the supported bobbin at a point outwardly beyond said filling, a suction chamber maintained under vacuum and having an inlet spaced below the supported bobbin, rotary elements having intermeshing teeth and disposed between the bobbin and said inlet to engage and break off said yarn after unwrapping thereof, and mechanism including a rotary element engageable with the yarn as it is unwrapped from said butt end and operable to draw the yarn away from the bobbin and finally break off the yarn adjacent said filling.
